PASSENGER VEHICLE SERVICE UNIT

Terrence J. Mulligan, 2044B Best Place, Aurora, Ill., and
John K. Morrison, 618 S. 4th St., Aurora, Ill. 60505

Filed Sept. 1, 1967, Ser. No. 8,478

Term of patent 14 years

(Cl. D23—73)

FIGURE 1 is a front elevational view of a passenger vehicle service unit embodying our new design.

FIGURE 2 is an elevational view taken from the right side thereof.

FIGURE 3 is an elevational view taken from the left side thereof.

FIGURE 4 is a top plan view thereof.

The dominant features of our design reside in the portions shown in full lines the undisclosed bottom and rear being plain and unornamented.

We claim:

The ornamental design for a passenger vehicle service unit, as shown and described.
